United States Patent Office

Des. 200,688
Patented Mar. 23, 1965

200,688

TRACTION PLATE

Ray P. Miles, 8575 N. Melody Lane, Northfield, Ohio

Filed July 17, 1963, Ser. No. 75,857

Term of patent 14 years

(Cl. D90—20)

Fig. 1

Fig. 2

FIGURE 1 is a top plan view of a traction plate showing my new design.

FIGURE 2 is a side elevational view of the traction plate.

The rear not shown is substantially plain.

I claim:

The ornamental design for a traction plate, as shown and described.
